DRINKING GLASS

John S. Cooper, Pensacola, Fla.

Application November 13, 1950, Serial No. 12,960

Term of patent 14 years

(Cl. D36—8)

To all whom it may concern:

Be it known that I, John S. Cooper, a citizen of the United States, residing at Pensacola, State of Florida, have invented a new, original, and ornamental Design for a Drinking Glass, of which the following is a specification, reference being had to the accompanying drawing, forming part thereof.

I claim:

The ornamental design for a drinking glass, as shown.

JOHN S. COOPER.
